UNITED STATES PATENT OFFICE.

KARL AUGENSTEIN, OF CRANSTON, RHODE ISLAND, ASSIGNOR TO AUTOMATIC GOLD CHAIN COMPANY, OF PROVIDENCE, RHODE ISLAND, A FIRM COMPRISING EDWIN F. M. SPEIDEL AND ALBERT R. SPEIDEL.

BRACELET END HOOK.

Application filed August 23, 1927. Serial No. 214,883.

This invention relates to a bracelet end hook for detachably securing the ends of a flexible bracelet to the bails or lugs of a wrist watch and has for its object to provide an end hook having a tongue for closing the opening to the hook with means for retaining the tongue in open position while the hook is being attached to or detached from the bails of a wrist watch.

10 A further object of this invention is to provide a latch part on the tongue which will engage a suitable formation on the shank of the hook to hold the tongue in open position until manually released.

15 With these and other objects in view, the invention consists of certain novel features of construction, as will be more fully described, and particularly pointed out in the appended claims.

20 In the accompanying drawings:

Figure 1 is a top plan view of a wrist watch with a bracelet secured thereto by my improved end hooks.

Figure 2 is a perspective view of the body 25 of the hook.

Figure 3 is a perspective view partly broken away of the shank and tongue members which are slidable relative to the body.

Figure 4 is a perspective view partly 30 broken away showing the body and sliding tongue and shank portion of the hook assembled.

Figure 5 is a central sectional view of the end hook.

35 Figure 6 is a section on line 6—6 of Figure 5.

Figure 7 is a view similar to Figure 5 showing the parts in extended position.

Figure 8 is a sectional view with the 40 spring and its abutment removed showing the tongue in open position to permit the entrance or detachment of the bail.

Figure 9 is a perspective view of the abutment for the spring.

45 Figure 10 is a perspective view of member for positioning and centralizing the spring in the body.

It is often found in practice difficult to 50 press the tongue of the bracelet end hook inwardly to open the hook and at the same time detach the hook from the bail of a wrist watch, and in order to simplify the manual manipulation for this purpose, I have provided a construction by which the

tongue will remain in open position while 55 the end hook is being detached from the watch, the same consisting of a latch mounted on the tongue to extend through an opening in the shank of the hook and snap over the edge of the opening which latch may 60 be released by pressure on its end to permit the hook to spring back by its inherent tension into engagement with the inner surface of the hook to close the opening thereto, and the following is a detailed description of 65 the present embodiment of this invention illustrating one means by which these advantageous results may be accomplished.

With reference to the drawings 10 designates the body of the end hook having a 70 top plate 11 with sides 12 folded therefrom and bent inwardly to provide flanges 13 which are also turned upwardly to form lips 14 to provide a rest for the abutment of the spring. A slide 15 is mounted in 75 the body 10 which has a shank portion 16 formed into a hook 17 at one end. This hook is closed by a resilient tongue 18 which engages the inner surface of the hook 17 by the inherent tension of the stock tending to 80 force the tongue in this direction.

The shank portion 16 is pierced or provided with an opening 19 in its top wall through which a latch part 20 carried by the tongue may extend when the tongue is 85 moved to open position as illustrated in Figure 8 and a detent 21 which is formed on this latch part snaps over the edge 22 of the opening 19 to retain the tongue in open position against its inherent closing 90 tension to permit the bail 23 of the wrist watch to be removed from the hook. When it is desired to release the tongue from this open position, it is merely necessary to press on the end 24 of this latch part to force the 95 same toward the bend of the hook thereby releasing the detent 21 and permitting the tongue to close by the inherent tension of its stock.

A spring 25 is positioned between the 100 folded end 26 of the slide 15 and an abutment 27 extending between the lip portions 14 against which the spring 25 acts to move the slide 15 into the body 10 to its contracted position. A bar 28 having a portion to enter 105 the coils of the spring is positioned at the fold 26 to centralize the spring and prevent it from moving out of alignment.

Sides 30 may be provided along the edges of the shank 16 to give a more finished appearance to the end hook and also serve the purpose of guiding the bail in its detachment from the hook and for cooperating with the latch part for preventing the bail from moving beneath the tongue and obstructing its opening movement thereof.

A bar 29 connects the sides 12 of the body 10 for attaching the hook to an adjacent bracelet link.

I have illustrated an end hook of a construction to permit extension between the body and hook proper, but it will be apparent that the construction by which the tongue is held in open position will operate fully as well in a construction of an end hook which has no extendibility.

The foregoing description is directed 20 solely towards the construction illustrated, but I desire it to be understood that I reserve the privilege of resorting to all the mechanical changes to which the device is susceptible, the invention being defined and 26 limited only by the terms of the appended claims.

I claim:

1. A bracelet end hook comprising a body, a sheet metal shank with an opening therein 30 extending from the body, said shank being formed into an open hook at its end, a sheet metal tongue for engaging the inner surface of said hook and closing the opening thereto

by the inherent tension of its stock, a latch part on said tongue for extending through the opening in said shank and a detent on said latch part to snap over the edge of said opening and hold said tongue in open position.

2. A bracelet end hook comprising a body, 40 a sheet metal broad shank extending therefrom with an opening therein and having a hook shaped end, a tongue for closing said hook end, and a latch portion carried by said tongue for extending through the opening 45 in said shank and snapping over the edge of said opening for retaining the tongue in open position, said latch being released by manual pressure on the end protruding through the opening in said shank.

3. A bracelet end hook comprising a body, a sheet metal shank with an opening therein extending from the body, said shank being formed into an open hook at its end, a sheet metal tongue for engaging the inner surface 55 of said hook and closing the opening thereto by the inherent tension of its stock, an integral latch part bent from the edge of said tongue for extending through the opening in said shank and an integral detent raised 60 from the stock of said latch part to snap over the edge of said opening and hold said tongue in open position.

In testimony whereof I affix my signature

KARL AUGENSTEIN.
